UNITED STATES PATENT OFFICE

JOSEPH C. McCUNE, OF EDGEWOOD, PENNSYLVANIA, ASSIGNOR TO THE WESTINGHOUSE AIR BRAKE COMPANY, OF WILMERDING, PENNSYLVANIA, A CORPORATION OF PENNSYLVANIA

RESERVOIR RELEASE VALVE

Application filed January 10, 1929. Serial No. 331,478.

This invention relates to release valve devices, and more particularly to a release valve device for releasing fluid under pressure from the auxiliary reservoir of a fluid pressure 5 brake system.

One object of my invention is to provide a release valve device having different positions, in one of which fluid is released from the auxiliary reservoir at one rate and in another position of which, fluid is released from the auxiliary reservoir at a different rate. 10

Other objects and advantages will appear in the following more detailed description of the invention.

15 In the accompanying drawings, Fig. 1 is a central sectional view of a release valve device embodying my invention and shown applied to an auxiliary reservoir; and Fig. 2 is a plan view of the release valve device.

20 It is sometimes desirable to release fluid from the auxiliary reservoir at a rapid rate, as in case a car is cut off from a train, and it is necessary to release the brakes on that car. At other times it is desirable to effect a 25 gradual release of fluid from the auxiliary reservoir, as at the head end of a train, in the case of an overcharged reservoir, and it becomes necessary to reduce the auxiliary reservoir pressure below brake pipe pressure 30 in order to release the brakes.

According to my invention, the release valve device may comprise a threaded nipple section 1, adapted to be screwed into an auxiliary reservoir 2, and a casing section 3, having screw-threaded engagement with the nipple section.

35 Disposed in a central cavity 4 of the casing 3 is a release valve 5 adapted to engage a seat rib 6. The valve is carried by a stem 7 which is guided in a central bore of the casing 3 and has a disk 8 secured at its upper end by a pin 9.

40 The valve is provided on its lower face with lugs 10, which are cut away to provide a seat for the end of a coil spring 11, the spring extending into a central cavity 12 of the nipple section 1 and having its lower end engaging a seat on the nipple. The valve 5 is also provided with peripheral guide lugs 45 13 to maintain the valve in axial alinement.

The stem 7 is provided adjacent to the valve 5 with an annular section 14 of greater diameter than the stem, the section 14 extending into the port opening 15, which is controlled by the valve 5.

55 For operating the valve stem 7, operating levers 16 and 17 are provided. The lever 16 is pivotally mounted on a pin 18 carried by lugs 19 of the casing 3 and is provided with a finger 20, the end of which engages the disk. The lever 17 is pivotally mounted on a pin 21 carried by lugs 22 and is provided with a finger 23 having forked end portions 24 adapted to straddle the finger 20 and engage 60 the disk 8.

65 Surrounding the coil spring 11 is another coil spring 25 which has one end in engagement with a seat in the the nipple section 1 and the upper end in engagement with a movable disk 26, mounted in an annular recess in 70 the casing section 3.

75 In operation, upon movement of either the lever 16 or 17, the disk 8 is operated to depress the stem 7. If it is desired to release fluid from the auxiliary reservoir at a slow rate, the lever is operated to move the valve 5 against the pressure of spring 11, until the lugs 10 engage the disk 26. This defines the position, since further downward movement 80 of the valve will be resisted by the added pressure of spring 25.

85 When the lugs 10 engage the disk 26, the enlarged section 14 still extends into the port opening 15, so that the rate of flow from the auxiliary reservoir is limited by the flow area between the section 14 and the cylindrical wall of the port opening 15. Fluid under pressure then flows from the auxiliary reservoir through the port opening 15 to the atmosphere by way of the atmospheric passage 27.

90 If it is desired to release fluid from the auxiliary reservoir at a rapid rate, one of the levers 16 or 17 is operated, so as to move the stem 7 until the disk 26 is moved, against the resistance of spring 25, to a seat on the nipple section 1. In this position, the valve 5 is shifted, so that the portion 14 does not extend into the port opening 15, and consequently 95 the rate of flow of fluid from the auxiliary reservoir is increased.

The lugs 10 are spaced apart to provide port area to insure ample venting capacity. When the valve 5 is moved down, the spring 11 may be compressed practically solid, and in such cases, air vented from the auxiliary reservoir can freely flow out through the port areas provided by the lugs 10.

While one illustrative embodiment of the invention has been described in detail, it is not my intention to limit its scope to that embodiment or otherwise than by the terms of the appended claims.

Having now described my invention, what I claim as new and desire to secure by Letters Patent, is:

1. In a fluid pressure release valve device, the combination with a release valve having an open position in which the release of fluid is restricted and another open position in which the release of fluid is at a more rapid rate, of a yielding stop for opposing movement of said valve from its first to its second mentioned position and means for actuating said valve.

2. In a fluid pressure release valve device, the combination with a release valve having an open position in which the release of fluid is restricted and another open position in which the release of fluid is at a more rapid rate, of yielding means for opposing movement of said valve to its first mentioned position, an additional yielding means for opposing movement of said valve from its first to its second mentioned position, and means for actuating said valve.

3. In a fluid pressure release valve device, the combination with a release valve having an open position in which the release of fluid is restricted and another open position in which the release of fluid is at a more rapid rate, of a spring opposing movement of said valve to its first mentioned position, a second spring opposing movement of said valve to its second mentioned position, and means for actuating said valve.

4. In a fluid pressure release valve device, the combination with a release valve having an open position in which the release of fluid is restricted and another open position in which the release of fluid is at a more rapid rate, of a movable member adapted to be engaged by said valve upon movement to its first mentioned position, a spring for opposing movement of said member, and means for actuating said valve.

5. The combination with an auxiliary reservoir of a fluid pressure brake system, of a release valve having one position in which fluid is released from the auxiliary reservoir at a restricted rate and another position in which fluid is released from the auxiliary reservoir at a more rapid rate, a yielding stop means for defining the first mentioned position of said valve, and means for actuating said valve.

6. In a fluid pressure release valve device, the combination with a release valve for controlling a release port and having a portion extending into said port for restricting the flow area of said port, said valve being movable to a position in which said portion does not restrict the flow through said port and means for actuating said valve.

7. In a fluid pressure release valve device, the combination with a release valve having one position in which the release of fluid is restricted and another position in which the release of fluid is at a more rapid rate, of a movable member, projections on said valve for engaging said member upon movement of said valve to its first mentioned position, a spring for opposing movement of said member, and means for actuating said valve.

8. In a fluid pressure release valve device, the combination with a release valve and a stem carried by said valve, of a lever, a finger operated by said lever and engaging said stem, a second lever, and a finger having forked ends engaging said stem and straddling the end of the other finger and operated by said second lever.

9. In a fluid pressure release valve device, the combination with a release valve and means for operating said valve, of a spring for opposing movement of said valve and surrounding a passageway through which fluid is vented by the operation of the release valve, and openings intermediate the spring and the valve for permitting the venting of fluid.

10. In a fluid pressure release valve device, the combination with a release valve and means for operating said valve, of a spring for opposing movement of said valve and surrounding a passageway through which fluid is vented by the operation of the release valve and openings intermediate the spring and the valve for permitting the venting of fluid independently of the spring.

11. In a fluid pressure release valve device, the combination with a release valve and a coil spring opposing movement of said valve and surrounding a passageway through which fluid is vented by operation of the release valve, of means associated with said valve and providing port openings independent of the spring for permitting the flow of fluid through said passageway.

In testimony whereof I have hereunto set my hand, this 7th day of January, 1929.

JOSEPH C. McCUNE.
